UNITED STATES PATENT OFFICE.

WALTER G. MACOMBER, OF LOS ANGELES, CALIFORNIA, ASSIGNOR TO MACOMBER MOTORS COMPANY, OF LOS ANGELES, CALIFORNIA, A CORPORATION OF CALIFORNIA.

MUFFLER.

1,226,789.

Specification of Letters Patent.

Patented May 22, 1917.

Original application filed April 27, 1915, Serial No. 24,196. Divided and this application filed January 31, 1916. Serial No. 75,306.

To all whom it may concern:

Be it known that I, WALTER G. MACOMBER, a citizen of the United States, residing at Los Angeles, in the county of Los Angeles and State of California, have invented a new and useful Muffler, of which the following is a specification.

This invention relates to improvements in mufflers for rotary internal combustion engines of the type shown in my prior Patents Nos. 933,316, September 7, 1909, and 1,042,018, October 22, 1912, and is a divisional application of my pending application Serial No. 24,916, filed April 27, 1915, the primary object being to provide a rotary muffler which will provide for an effective air cooling of the motor and a thorough exhausting of the spent gases from the motor cylinders as well as the muffling of the noises of the explosions.

An object of this invention is to provide a muffler of the character described which will effectively muffle the noises of the explosions without retarding the motor action to an appreciable extent and which may be simply and cheaply constructed.

Other objects and advantages will appear from the subjoined detail description.

The accompanying drawings illustrate the invention.

Figure 1 is a top plan view of the engine equipped with my improved muffler showing parts broken away and in section;

Fig. 2 is a cross sectional view taken on line 2—2 of Fig. 1;

Fig. 3 is an enlarged fragmentary detail sectional view of the muffler showing the manner of connecting the exhaust tubes therewith; and

Fig. 4 is a fragmentary vertical sectional view of the muffler showing the exhaust port thereof.

Referring to the drawings by characters of reference, A designates a rotary engine which includes a casing 1, a frusto-conical air intake funnel 2 connected at its smaller end with one side of the casing and a series of exhaust valves 3. In the drawings there is shown one of the exhaust valves and part of one of the engine cylinders 4. Each of the valves communicates with a chamber 5 which is connected with one end of a horizontal exhaust tube 6. The motor, includ-

ing the cylinders 4, exhaust valves 3 and tubes 6, rotates within and is spaced from the walls of the casing 1 so as to provide for the free circulation of air about the motor and working parts thereof, air being caused to pass through the casing and about the working parts of the motor by my improved rotary muffler which will be later described and which sucks the air through the funnel 2.

The casing 1 at the side opposite to the funnel 2 is provided with an enlarged circular muffler casing 7 through which projects the shaft 8 of the motor A, a bearing 9 being carried by and projecting from the casing 7 so as to receive the shaft 8.

Rotatably mounted upon the shaft 8 within the casing 7 is a muffler designated 10 as an entirety which is circular and comprises a frusto-conical circular body plate 11 rotatably mounted upon the bearing 9, a rotatable bearing 12 being interposed between the plate 11 and bearing 9. The plate 11 is provided with a peripheral attaching flange 13 which is secured to flanges 14 on the revolving cylinders of the engine A by bolts 15 so as to provide for the rotation of the muffler with the cylinders.

Secured upon the other face of the peripheral attaching flange 13 is a channel shaped muffler ring 16 of considerably less diameter than the casing 7. An inwardly extending annular flange 17 is carried by the ring 16 and abuts the attaching flange 13, the bolts 15 being passed through the flanges 14 and 17, and the flanges 14 have screw-threaded openings to receive the screw-threaded ends of the bolts.

Radially mounted within the ring 16 are segmental muffler plates 18 which are secured to and in spaced overlapping relation to one another by bolts 19 which pass through the plates and ring. Spaced blocks 20 are mounted on the bolts 19 and are interposed between the several plates to space them. The longitudinal edges of the plates abut the opposed inner faces of the muffler ring and form tortuous compartments extending around the ring. An opening 20^a is formed in the outer wall of the casing 7 and communicates the casing with the atmosphere whereby the muffler and adjacent parts will be kept cool.

The exhaust tubes 6 are extended into the casing 7 and are connected with the exhaust ring 16 as at 21, openings 22 being provided in the exhaust ring to communicate the latter with the exhaust tubes. The casing 7 has upon its inner wall a circular opening 23 through which the tubes 6 pass, said opening being sufficiently large to provide for the passage of air from the casing 1 into the casing 7 at points surrounding the tubes 6.

The peripheral wall of the ring 16 is provided at spaced points with outlet orifices 24 and extending outwardly from said peripheral wall are parallel fan blade-supporting flanges 25 between and secured to which are spaced transverse fan blades 26 which are slightly curved in cross section.

The muffler plates 18 form series of circular compartments or passages within the exhaust ring 16, and to provide for communication of the passages with each other, there are formed in each muffler plate a series of orifices 27.

25 The operation of the muffler is as follows: When the motor A is operated, the exhaust valves 3 allow the exhaust gases to pass through the tubes 6 into the muffler ring 16 of the muffler 10. The exhaust gases in the 30 muffler pass from one compartment to another and out through the orifices 24. The muffler 10 rotates with the engine and the fan blades 26 carried on the periphery of the muffler produce a suction within the casings 7 and 1 and causes air to be drawn 35 through the funnel 2, which communicates with the atmosphere, and into the casing 1 about the motor, thus cooling the motor. An exhaust pipe 28 communicates with the 40 lower end of the casing 7 and the air which has been drawn through the casing 1 is exhausted through said pipe together with the exhaust gases which escape from the muffler through the exhaust orifices 24. The 45 fan blades 26 blow the air and gases out through the pipe 28. The rapid exhaust of the air through the casing 7 causes the exhaust gases within the ring 16 to be sucked through the exhaust orifices 24 and results 50 in a thorough exhausting of the spent gases from the motor cylinders and muffler. The arrangement of muffler plates 18 muffles the noises of the explosions in the cylinders without retarding the motor action to any appreciable extent and the muffler itself not only 55 thoroughly exhausts the spent gases from the cylinders and deadens the noise of the explosion but causes air to be drawn rapidly through the motor and exhaust casings 60 so as to keep the engine cool.

I claim:

1. In a muffler the combination with an internal combustion engine including a casing surrounding the engine and having communication with the atmosphere, of a

rotary muffler operatively associated with the engine, a casing for the muffler communicating with the engine casing and having an exhaust, and fan blades carried by the muffler to produce a draft of air through the engine and muffler casing.

2. In a muffler the combination with an internal combustion engine including a casing having communication with the atmosphere, a rotary muffler operatively associated with the engine, a casing for the muffler having an exhaust port and communicating with the engine casing, and fan blades carried by the muffler, said muffler having exhaust orifices opening between the fan blades.

3. In a muffler the combination with a rotary internal combustion engine including a casing, said casing communicating with the atmosphere, of a rotary muffler operatively associated with the engine, a casing for the muffler having communication with the engine casing and an exhaust port, exhaust tubes connected with the engine and muffler, said muffler comprising a series of compartments having outlet orifices, and a fan carried by the muffler.

4. In a muffler the combination with a rotary internal combustion engine including a drive shaft, a rotary muffler journaled from the drive shaft and connected for rotation with the engine, said muffler comprising a ring having a series of compartments therein, said compartments communicating with each other, said ring having orifices in its periphery, a casing for the muffler having an exhaust port, and fan blades carried on the periphery of the ring to force the exhaust gases out of the exhaust port in the muffler casing.

5. In a muffler, an engine shaft, a hollow ring mounted for rotation upon said shaft and having intake ports therein, a plurality of radially mounted segmental muffler plates mounted within the ring in staggered spaced relation to each other, said plates having orifices therein, said ring having exhaust ports in its peripheral wall, a casing for the muffler having an exhaust port, and curved fan blades mounted upon the peripheral wall of the muffler.

6. In a muffler the combination with a rotary internal combustion engine including a casing and a drive shaft, of an intake funnel connected with the casing and communicating with the atmosphere, an annular channel shaped muffler ring rotatably mounted upon said shaft and connected for rotation with the engine, a casing for said muffler communicating with the engine and having an exhaust port, said ring having a plurality of compartments therein, said compartments having communication with each other, exhaust tubes connected with the engine and ring, said ring having exhaust

ports in the peripheral wall thereof, and fan blades mounted upon said peripheral wall of the ring.

7. A rotary engine having a casing, a shaft mounted in the casing, cylinders rotatably mounted on the shaft, a muffler connected with the cylinders for rotation therewith, a casing for the muffler communicating with the engine casing, tubes connecting the cylinders with the muffler, and fan blades for creating a circulation of air through the engine and muffler casing carried by the muffler and rotating in the muffler casing, said casings having communication with the atmosphere.

8. In a muffler the combination with a rotary internal combustion engine including a casing housing the engine communicating with the atmosphere at its ends, a rotary muffler operatively associated with the engine, said muffler having exhaust orifices therein, means to communicate the muffler with the exhaust ports of the engine, said muffler being mounted within the casing, and means carried by the muffler for creating a circulation of air through the casing upon rotation of the muffler.

9. In a muffler the combination with a rotary internal combustion engine including a casing, said casing communicating with the atmosphere, of a rotary muffler operatively associated with the engine, said muffler being housed in the casing, exhaust tubes connected with the engine and muffler, said muffler comprising a series of compartments having outlet orifices, and means for creating a circulation of air through the casings upon rotation of the muffler.

10. In a muffler the combination with a rotary internal combustion engine including a casing surrounding and housing the engine and having communication with the atmosphere at its ends, and a muffler fixed to and adapted to rotate with the engine, said muffler being mounted within the casing, said casing being spaced circumferentially from the engine whereby a draft of air will pass through the casing and about the engine upon rotation of the muffler.

In testimony whereof, I have hereunto set my hand at Los Angeles, California, this 26th day of January, 1916.

WALTER G. MACOMBER.
